US00D428411S

United States Patent

[19]

Poole et al.

[11] Patent Number: Des. 428,411

[45] Date of Patent: ** Jul. 18, 2000

[54] **INTEGRATED DESKTOP PERSONAL COMPUTER WITH MODULAR LCD DISPLAY**

D. 354,949 1/1995 Yao D14/337
D. 361,550 8/1995 Mundt et al. D14/337
D. 383,733 9/1997 Mieki D14/336

[75] Inventors: **Anton Poole; Yutaka Kazamaki; Paul D. Holder**, all of Dakota Dunes, S. Dak.; **Benjamin Pei-Ming Chia**, Cupertino, Calif.; **Chris Lenart**, San Francisco, Calif.; **Robert Brunner**, Los Gatos, Calif.

Primary Examiner—Freda Nunn
Attorney, Agent, or Firm—Anthony Claiborne

[73] Assignee: **Gateway, Inc.**, N. Sioux City, S. Dak.

[**] Term: **14 Years**

[21] Appl. No.: **29/111,864**

[22] Filed: **Oct. 5, 1999**

[51] LOC (7) Cl. **14-02**

[52] U.S. Cl. **D14/337**

[58] Field of Search D14/374, 375, D14/126-129, 336, 337; 345/104, 133, 156, 168, 173; 348/180, 184, 325, 739; 349/1, 2, 11; 364/708.1
